UNITED STATES PATENT OFFICE

JOSEPH M. HAUSE, OF TULSA, OKLAHOMA

ADJUSTABLE SHADE HOLDER AND GUIDE

Application filed June 14, 1928. Serial No. 285,337.

This invention pertains to improvements in window shade holders and guide means and consists briefly in providing a pair of hollow guide members adapted to be secured to the opposing vertical portions of the usual window frame and between which the present novel shade carrying means are disposed and provided with adjustable means complementary to the guide members whereby the carrier may be moved vertically and set in any predetermined position without any inconvenience and in a quick and efficient manner.

An important object of the invention is to provide a shade carrier and guide device of the above character which will permit the shade roll to be adjusted to any position desired between the aforesaid guide members, whereby the top sash of the usual window construction may be opened without fearing any damage to the curtain as a result of the wind blowing therethrough.

Another important object resides in the provision of novel means whereby the shade roller carrier may be quickly adjusted to the position desired, by the actuation of simple and easily operable finger levers arranged on a pull rod associated with the end of the shade strip for actuating the controlling means.

Still another object resides in the particular journal adaptability of the structure, wherein the same may be employed in conjunction with window frames of different construction and which also serves to provide curtain carrying means whereby the shade strip may be maintained in closed relation to the sashes of the window so as to assure privacy, in that the pull rod member of the invention is prevented from swinging outwardly from the guide members.

After reading the following specification and claims, other important objects and advantages of the invention will readily become apparent.

In the drawings:

Figure 1 represents a front side elevation in partial sectional view, disclosing the invention in its entirety.

Figure 2 represents a longitudinal sec-

tional view through the pull rod member, to which the end of the sash strip is attached.

Figure 3 is a perspective view of the manually operable means for releasing the shade carrier from its adjusted position.

Figure 4 is a cross sectional view through the hollow core rod taken substantially on the line 4-4 of Figure 2.

Figure 5 is a perspective view of a detail of the shade carrier.

Figures 6 and 7 are perspective views of the vertical guide members.

Figure 8 is a perspective view of the detail complementary to the detail disclosed in Figure 5, and of substantially the same construction, which in this view is shown with the associated parts assembled, and

Figure 9 is a perspective view of a fragmentary portion of the connecting means between the details disclosed in Figures 5 and 8 respectively in fragmentary view, and disclosing the shade hanger arranged for slideable movement thereon.

Referring more particularly to the drawings wherein like numerals designate like parts, a pair of channel bars of substantially U-shaped construction are designated by numerals 1-1 and are arranged and secured to the vertical opposing portions of the usual window frame by suitable screws 2, arranged through the bight portions thereof. The longitudinal edge portions of each guide bar 1 are bent inwardly as at 3, in angular spaced relation. The opposing longitudinal edges of the guide bars 1 are formed with corresponding notches 4 from an intermediate point on the guide bar to the lower end thereof.

These notches are produced by forming a downwardly and gradually inwardly disposed butt to provide shoulders 5, upon which the shade carrier which will be fully described hereinafter may be supported.

Slidable within each of the guide bars 1 is a U-bar 6, having a block 7 secured between its flanges at its upper end and provided with an L-shaped plate 8 secured at its upper end to a point inwardly from the lower end of the bar so that its foot portion

100

9 will project beyond the bight portion thereof.

The L-shaped plate 8 is constructed of spring metal so that by engaging the plate under the notch portion 10 at the lower end of the U-bar 6, the same may be forced backwardly beyond the bight portion thereof by means projected through the notch of the bar. The foot portions 9 of the spring plates 8 are adapted to engage optionally in the notches 4, in the manner shown in Figure 1.

A pair of elongated rods 11—11 are threaded at their opposite ends for engagement in the blocks 7 and are slidable within the space 15 between the opposed longitudinal edges of the guide bars 1, allowing the movement of the U-bar 6.

A pair of clamp plates 12—12 are each formed with a corrugation at its respective 20 ends, so that the plates may be applied to opposite sides of the rods 11—11 so that the rods engage within the channeled sides of the corrugations. The plates may be secured thus in position by suitable means, which 25 may be loosened for permitting the plates to be slid along the rod to accommodate shade rolls of different dimensions. The outermost plate has secured thereto a shade bracket 13 which may be of conventional design. A 30 shade bracket is thus mounted on the rods 11—11 at each end thereof, in the manner clearly shown in Figure 1. The innermost plate of each of said sets of clamp plates is provided with a laterally projecting arm 14.

The shade strip A of the usual width and length is rolled on a spring shade roll, in the usual manner for support upon the bracket 13. The free end of the shade strip is secured around a tubular draw bar 15, which 40 has a plug 16, arranged within each open end thereof. A portion of each plug projects beyond the adjacent end of the pull bar and is of conical shape to permit its engagement within the inwardly disposed longitudinal 45 edge portions of the guide bars 1—1. Each plug 16 is formed with a longitudinal bore therethrough, the same opening at its outer end, through the apex of the conical portion thereof.

Secured within the tubular draw bar 15 is a barrel 17 having one end portion reduced as at 18 and internally threaded, while its opposite end is also reduced, externally threaded, and longitudinally split, so that 55 a jamb nut 19 threaded thereon will effect a means for providing a frictional slide bearing for the elongated slidable rod 20, which projects through this reduced end of the barrel and is equipped with a laterally projecting lever 21 projecting through an opening 22 in the barrel and a registering opening 23, in the hollow pull rod 15.

The nut 19 is provided with a laterally projecting lever 24 which also projects through 65 the opening 23 in the hollow pull bar. A

second rod 25 is threaded at one end into the internally threaded end 18 of the barrel and normally terminates at its opposite end flush with the outer end of the adjacent plug 16. The outer end of the rod 20 also terminates normally flush with the outer end of the adjacent plug 16 while the inner end thereof is tensionally connected to the adjacent inner end of the rod 25 by a coiled spring 26, which spring serves to maintain the rods 20 and 25 respectively in retracted position. An eye member 27 is secured to the bottom portion of the pull bar 15 to permit the attachment of a pull cord thereto.

In operating the shade carrier portion of the invention, let it be assumed that the parts are disposed in the position shown in Figure 1. In this position the pawl plates 8 are in engaged position with certain of the notches 4. Although not shown in the drawings, the shade roll is mounted upon the brackets 13, which brackets are slidably supported upon the pair of connecting rods 11—11 which have their opposite ends connected to the complementary U-bars 6. Obviously, by pressing the hand lever 21, toward the lever 24, the rod 20 will be projected through one end of the pull bar 15, while the other rod 25 will be projected through the opposite end of the bar by the relative movement of the barrel 17. The end portions of the movable bars 20 and 25 engaging the spring pawl plates 8 through the notches 10 in the lower ends of the U-bars 6, will permit the disengaging of the foot portion 10 thereof from engagement with the notches 4. This disposition of parts now allows the person to move upwardly or downwardly the pull rod 15, which also results in the downward movement of the bars 6, ultimately resulting in the location of the shade roll at a predetermined position downwardly between the guide-bars 1—1.

Although the preferred embodiment of the invention is disclosed in the drawings, changes in the shapes, size or materials may be resorted to, without departing from the spirit of the invention or the scope of the appended claims.

Having described my invention, what is claimed as new is:

1. In a guide for window shades comprising a pair of slotted uprights, said uprights being secured to the opposing vertical portions of the usual window frame, a shade roll carrier slidable between said guide members, a pull bar having its ends engaged within the slots of the uprights and being secured to the free end of the usual shade strip, means on the carrier complementary to the upright whereby the carrier may be adjusted vertically between the uprights, and means on the pull bar for releasing said adjusting means.

2. In a guide for window shades comprising a pair of slotted uprights, said uprights

being secured to the opposing vertical portions of the usual window frame, a shade roll carrier slidable between said guide members, a pull bar having its ends engaged within the slots of the uprights and being secured to the free end of the usual shade strip, one of said uprights being formed with longitudinally spaced notches, spring pawl means on said carrier engageable with said notches for permitting the vertical adjustment of the carrier, and means on said pull bar for releasing said pawl means.

3. In a guide for window shades comprising a pair of slotted uprights, said uprights being secured to the opposing vertical portions of the usual window frame, a shade roll carrier slidable between said guide members, a pull bar having its ends engaged within the slots of the uprights and being secured to the free end of the usual shade strip, one of said uprights being formed with longitudinally spaced notches, spring pawl means on said carrier engageable with said notches for permitting the vertical adjustment of the carrier, means on said pull bar for releasing said pawl means, said means consisting of a rod slidable within said pull bar and adapted to be projected beyond one end thereof for disengaging the pawl means from engagement with the upright.

In testimony whereof I affix my signature.
JOSEPH M. HAUSE.
